UNITED STATES PATENT OFFICE.

GEORGE DEAN BAILEY AND FRANK EDWARD RICE, OF DETROIT, MICHIGAN, ASSIGNEES TO GEARLESS DIFFERENTIAL CO., A CORPORATION OF MICHIGAN.

DIFFERENTIAL MECHANISM.

1,180,465.

Specification of Letters Patent. Patented Apr. 25, 1916.

Application filed June 23, 1915. Serial No. 32,701.

To all whom it may concern:

Be it known that we, GEORGE DEAN BAILEY and FRANK EDWARD RICE, citizens of the United States, and residents of the city of Detroit, in the county of Wayne and State of Michigan, have invented certain new and useful Improvements in Differential Mechanisms; and we do hereby declare that the following is a full, clear, and exact description of the same, reference being had to the accompanying drawings, and to the numerals of reference marked thereon, which form a part of this specification.

The general type of differential gear used in motor car rear axles, is objectionable in many respects, chiefly among which may be mentioned the fact that that rear wheel to which is offered the least tractive resistance, receives the most power from the differential, while on the other hand the other wheel having the most tractive resistance receives the least power. The result of this unequal distribution of the drive causes the car to be stalled if for any reason one driving wheel sinks into a muddy or sandy portion of the road, so that the wheel cannot secure proper traction, the other wheel not receiving a sufficient amount of the power to propel the car. Then, too, skidding results if for any reason the rear wheels do not roll upon the same kind of surface, as for instance with one wheel rolling on the crown of a stone road and the other in dirt or sand at the side, the constantly changing resistance to the respective wheels causes a shifting of power from first one to the other, so that a dangerous side sway is set up, resulting, as stated, in skidding and possible accident.

The present invention relates to an improved type of differential wherein a positive direct drive is imparted to the wheel to which the greatest tractive resistance is offered, so that as a consequence where the wheels are revolving at different speeds, due to some cause or another, the slower revolving wheel receives the power to propel the car, thus obviating skidding, side-sway, or stalling of the car.

It is an object therefore of this invention to construct a differential mechanism provided with differentially movable ratchet wheels and tilting lever pawls for engagement therewith to drive the same simultaneously or differentially, either forward or reversely, as the case may be with the direct

drive being imparted in the case of differential movement, to the slower revolving wheel of the vehicle.

It is also an object of this invention to construct a differential mechanism embracing a unitary casing within which are mounted small walking beam or tilting levers which act to interlock the casing with ratchet wheels which are rigidly associated with axle sections, in a manner permitting a differential movement to take place between said ratchet wheels, insuring the drive being imparted always to the slower revolving wheel of the vehicle.

It is also an object of this invention to construct an improved type of differential mechanism wherein the respective axle sections of the sectional driving axle have secured thereon ratchet wheels, adapted to be driven differentially from an integral driving segment or casing by co-action with walking beam spring impelled pawls serving to interlock the segments with the ratchet wheels, one end of each pawl adapted to drive one of the ratchet wheels in one direction and the other ends of the same pawls adapted to drive the other ratchet wheel in the opposite direction, thus preventing the driving means for the different directions of rotation, forward and reverse, to be engaged simultaneously.

It is furthermore an important object of this invention to construct a differential mechanism wherein tilting levers are mounted in a driving segment casing to co-act with ratchet wheels secured on axle sections to drive the same, one end of each of said levers adapted to drive one ratchet wheel in one direction and the other end of each lever adapted to drive the other ratchet wheel in an opposite direction, the construction, due to the tilting action of the levers, preventing both ends of the same lever to be engaged simultaneously with the ratchet wheels and permitting the levers to be thrown out of engagement with both of said ratchet wheels against spring pressure when circumstances require.

It is finally an object of this invention to construct a simplified and silently operating differential mechanism wherein the slower revolving wheel of a vehicle receives the drive where a differential movement is necessitated, and a mechanism which may be easily installed within the axle housing.

for replacement of the differential gear on motor cars already in use.

The invention (in a preferred form) is illustrated in the drawings, and hereinafter more fully described.

In the drawings: Figure 1 is a fragmentary reduced view with parts in section and parts in elevation, illustrating a differential mechanism embodying the principles of our invention within the housing of a rear axle. Fig. 2 is a central horizontal section taken through the differential mechanism, with parts shown in elevation. Fig. 3 is an interior end view of the mechanism with a cover plate or end member detached. Fig. 4 is a detail section taken on line 4-4 of Fig. 2. Fig. 5 is a central vertical section taken through the driving casing and pawl carrying element of the gear. Fig. 6 is a central section taken on line 6-6 of Fig. 5. Fig. 7 is a detail section taken on line 7-7 of Fig. 6. Fig. 8 is a detail elevational view of one of the tilting lever or walking beam pawls. Fig. 9 is a detail sectional view illustrating the method of mounting one of the hardened steel seats in place in the driving element. Fig. 10 is a similar view thereof, showing the same mounted in position.

As shown in the drawings: The reference numeral 1, indicates as a whole a differential housing, into which the ends of axle sections 2, of a sectional driving axle extend. Also extending into the differential housing 1, at right angles to the axle sections 2, is a drive shaft 3, mounted in suitable bearings provided for the purpose, and at its end having a bevel pinion 4, secured thereon. Said bevel pinion 4, meshes with a large bevel gear ring 5, which is rigidly secured to the peripheral flange 6, of a double segment housing or cage member 7. Detail views of said cage or housing 7, are shown in Figs. 5, 6; and 7, and it will be seen by reference thereto that, the same is formed with a central hub 8, into which the extreme ends of the axle sections 2, project, as shown in Fig. 2. Four bolts 9, extend through apertures provided for the purpose in said hub 8, fitting, as shown in Fig. 2, into the recessed or grooved ends of the axle sections to maintain the same rotatably but positively associated with said cage or housing and prevent withdrawal of a section therefrom, except by removal of the proper bolts 9.

Projecting radially outwardly from said hub 8, as clearly shown in Figs. 2, 5, and 6, are extensions 10, in the ends of which are engaged in any suitable manner hardened steel seats 11. The purpose of said hardened steel seats 11, is to receive tilting lever pawls 12, resting thereon under the stress of spiral compression springs 13, seated in plugs 14, which are threaded into apertures

provided in the outer wall of the housing or cage 7. Inwardly extending flanges or webs 15, are provided on the inner surfaces of the outer curved walls of the cage 7, and formed centrally in each of said webs is a rounded V-notch 16, adapted to engage the end of a tilting lever pawl 12, in the manner shown in Fig. 3.

As clearly shown in Figs. 5 and 7 a portion of the web 15, on one side of the V-notch 16, is enlarged, as denoted by the reference numeral 17, and recessed to receive a hardened steel pin 18, therein adapted to bear against the end of the tilting lever pawl 12, when the same is in driving position. Said hardened steel pins 18, are associated with the housing or cage 7, in a novel manner to insure positive retainment thereof, and for this purpose, as clearly shown in Figs. 9 and 10, said pins are peripherally recessed just beneath the head thereof, and upon being driven into the aperture provided therefor in the enlarged portion 17, of the cage, the metal forced outwardly a slight amount around the upper end of the aperture, as denoted by the reference numeral 19, is forced into the recessed portion of the pin in the manner shown in Fig. 10, so that the pin is thus positively held in place. The inner adjacent ends of the axle sections 2, are squared, and secured on each thereof are ratchet wheels 20, adapted to receive the ends of the respective tilting lever pawls 12, seated therein for the purpose of effecting driving engagement between the housing or cage 7, and said ratchet wheels. Secured upon the hub portion 8, of the cage 7, and retained positively associated with said cage by means of pins 21, are pick-up plates 22, which as clearly shown in Fig. 2, lie flat against the inner faces of the respective ratchet wheels 20, and each of said plates, as clearly shown in Fig. 4, is provided in its edges with a curved recess or notch affording an abutment 23, at points diametrically opposite one another.

Fitted rotatably around the hubs of the respective ratchet wheels 20, and also around said axle sections 2, are end members or cover plates 24, each having a long extended hub 25. Said cover plate members 24, are rigidly associated with the housing 7, by means of bolts 26, four of which are provided extending through apertures in said cover plates and through apertures registering therewith provided in the webs 15, of said housing. The extended hubs 25, of said cover plate members 24, are journaled in suitable ball bearings 27, provided in the differential housing 1, said bearings being of a familiar and well known type of construction, and mounted alongside thereof and surrounding the axle sections 2, are felt washers 28, which serve to confine the grease

within the differential housing for the mechanisms therein, preventing leakage along the axle sections.

The operation is as follows: Under normal operating conditions the driving bevel pinion 4, drives the bevel gear ring 5, and the cage or housing 7, therewith, and one end of each of the respective tilting lever pawls 12, serves to drive the respective ratchet wheels 20, due to the fact that the V-notches 16, in the web of said cage or housing bear upon the ends of the pawls in the manner shown in Figs. 3 and 4, holding one of the ends of the respective pawls in the notches 16 of the ratchet wheels. One end of each pawl is adapted to drive one ratchet wheel in one direction and the other end of the same pawl is adapted to drive the other ratchet wheel in an opposite direction, and at no time can both ends of a pawl be in engagement with both of the respective ratchet wheels 20.

Referring to Fig. 2, the topmost pawl 12, is in driving engagement with the right hand ratchet wheel 20, and the lower pawl 12, is in engagement with the left hand ratchet wheel 20, so that the respective axle sections 2, rotate together and at the same speed. In the event of a differential action taking place, as when the vehicle turns a corner, thus causing the outermost wheel to rotate faster, and the axle section and respective ratchet wheels therewith, the pick-up plate 22, serves to throw the end of the pawl, which is in driving engagement, upwardly out of the notch in the ratchet wheel, due to the fact that the ratchet wheel drives or thrusts the end of the pawl against the abutment 23, of said pick-up plate, and at such a time both ends of that particular tilting lever pawl are out of engagement with the ratchet wheels, the pawl being lifted away from the hardened steel seat 11, against the compression of the spring 13. That pawl, however, driving the inner or slower revolving vehicle wheel through its respective ratchet wheel on its axle section, remains in engagement. Assuming the tilting lever pawls to be in the position shown in Fig. 2, for driving forwardly, in the event that the rear wheels of the vehicle coast, and thus tend to turn faster than the driving mechanism therefor, said pawls reverse their position, that is the respective pawls shown in Fig. 2, tilt counterclockwise from the position shown to interlock the respective ratchet wheels 20, with the housing or cage 7, so that the ratchet wheels drive the housing and consequently the bevel gears in the same manner as the ordinary differential gear. The mechanism operates automatically, however, to throw out an interlocking pawl if for any reason, even when coasting, one of the wheels is caused to rotate faster than the other, and in such an event of course the

pawl which is thrown out of locked position is lifted outwardly from its seat 11, against the compression of the spring 13, with both of its ends disengaged from the ratchet wheels. This construction is extremely simple and adapts itself well for interchangeability on cars provided with the usual stock differential, and may be easily assembled, consisting, as it does, of few parts. There is practically no wear upon the mechanisms inasmuch as under ordinary conditions the entire gear rotates as a unit in the respective ball bearings 27, and the ratchet wheels and pawls being of hardened steel, as well as the pin 18, against which the ends of the pawls bear when in driving engagement between the ratchet wheel and housing, precludes any appreciable wear on the mechanism.

We are aware that various details of construction may be varied through a wide range without departing from the principles of this invention, and we therefore do not purpose limiting the patent granted otherwise than necessitated by the prior art.

We claim as our invention:

1. In a device of the class described the combination with axle sections, of ratchet wheels secured on each thereof, a carrying element journaled between said ratchet wheels, tilting pawls mounted transversely on said carrying element, one end of each thereof in position to engage one of said ratchet wheels, and the other in position to engage the other of said ratchet wheels, and means integral with said carrying element adapted to bear upon the outer ends of said pawls when the same are tilted into engagement with the ratchet wheels to impart a drive to said wheels through said pawls.

2. In a device of the class described the combination with axle sections, of ratchet wheels secured thereon, means mounted pivotally between said ratchet wheels adapted to engage either one thereof for driving, but prevented from engaging both thereof simultaneously, a carrying element for said means, said means capable of tilting in one direction and pivoting in another direction, and driving mechanism integral with said element for contact with the ends of said means to thrust the same into engagement with said ratchet wheels to impart a drive thereto.

3. In a device of the class described the combination with independently rotatable axle sections, of ratchet wheels rigidly secured thereon, a carrying element journaled on said ratchet wheels having recesses therein, tilting spring impelled pawls mounted transversely in said carrying element, one end of a pawl adapted to engage a ratchet wheel for driving in one direction and the other end of said pawl adapted to engage the other ratchet wheel for driving in the

other direction, driving mechanism integral with said carrying element for wedging the ends of said pawls into driving engagement with the ratchet wheels, and means driving said integral mechanism and carrying element.

4. In a differential mechanism of the class described the combination with axle sections, of ratchet wheels rigidly secured thereon, said ratchet wheels having extended hubs on each side thereof, a cage fitting therebetween and journaled thereon, end plates bolted to said cage and journaled on the outer hub extensions of said ratchet wheels, and tilting lever pawls mounted in said cage adapted to effect driving engagement between the same and said ratchet wheels to drive the axle sections.

5. In a differential mechanism of the class described the combination with axle sections having ratchet wheels secured thereon, of a cage member journaled between said ratchet wheels, end plates bolted to said cage and journaled on the outer hub extensions of said ratchet wheels, tilting pawls pivotally mounted in said cage adapted to interlock the same with one or both of said ratchet wheels, and means secured in said cage to throw said pawls out of driving engagement to permit differential movement of said ratchet wheels.

6. In a differential gear of the class described the combination with ratchet wheels, of tilting lever pawls adapted to engage said ratchet wheels, and an integral driving and carrying element for said pawls adapted to contact the outer ends of said pawls to wedge the ends thereof in said ratchet wheels to transmit the drive to said ratchet wheels.

7. In a device of the class described the combination with a housing; a bevel gear ring secured thereon adapted to receive a drive, axle sections extending into said housing, ratchet wheels secured upon said axle sections, bolts extending through said housing adapted to retain the axle sections engaged within the housing, and tilting pawl

levers mounted within said housing adapted to effect driving engagement only at their ends between the housing and said ratchet wheels to permit differential movement thereof.

8. In a device of the class described the combination with the axle sections of an axle, of ratchet wheels secured thereon, a carrying element disposed between said ratchet wheels, tilting pawls mounted on said carrying element for engagement with said ratchet wheels, and mechanism disposed peripherally around said ratchet wheels and integral with said carrying element to wedge the ends of the pawls into engagement with said ratchet wheels to impart a drive thereto.

9. In a device of the class described the combination with axle sections, of ratchet wheels secured thereon, a carrying element journaled therebetween, spring impelled tilting pawls pivotally mounted on said carrying element, the ends thereof adapted to engage said ratchet wheels, and integral extensions on said carrying element adapted to wedge the ends of said pawls into engagement with said ratchet wheels to impart a drive thereto.

10. In a device of the class described the combination with axle sections, of ratchet wheels secured thereon, hub extensions formed on the inner sides of said ratchet wheels, a carrying element journaled on said hub extensions, tilting pawls mounted on said carrying element adapted to swing into engagement with said ratchet wheels, and extensions integral with said carrying element to wedge the ends of said pawls into engagement with said ratchet wheels to impart a drive thereto.

In testimony whereof we have hereunto subscribed our names in the presence of two subscribing witnesses.
